UNITED STATES PATENT OFFICE

146,577

DESIGN FOR A ROSARY OF THE STATIONS OF THE CROSS

John C. Kelley, New Haven, Conn.

Application December 27, 1945, Serial No. 125,056

Term of patent 14 years

(Cl. D45—16)

To all whom it may concern:

Be it known that I, John C. Kelley, a citizen of the United States, residing in New Haven, county of New Haven, and State of Connecticut, have invented a new, original, and ornamental Design for a Rosary of the Stations of the Cross, of which the following is a specification, reference being had to the accompanying drawing, forming a part thereof.

The figure is a plan view of a Rosary of the stations of the Cross showing my new design.

The rear faces of each of the several medallions have embossed lettering thereon.

I claim:

The ornamental design for a Rosary of the Stations of the Cross, as shown and described.

JOHN C. KELLEY.
